UNITED STATES PATENT OFFICE

JAMES C. PAPE, OF NEW YORK, N. Y.

DESIGN FOR A SOLE FOR A WOMAN'S SHOE

Application filed April 25, 1931. Serial No. 39,627. Term of patent 14 years.

To all whom it may concern:

Be it known that I, JAMES C. PAPE, a citizen of the United States, residing at New York, in the county and State of New York, have invented a new, original, and ornamental Design for a Sole for a Woman's Shoe, of which the following is a specification, reference being had to the accompanying drawing, forming a part thereof.

The figure is a bottom plan view of a sole for a woman's shoe showing my new design.

I claim:

The ornamental design for a sole for a woman's shoe substantially as shown.

JAMES C. PAPE.
